(57) **CLAIM**

The ornamental design for a road construction machine, as shown and described.

DESCRIPTION

FIG. 1 is a left side view of a design for a road construction machine of the present invention.

FIG. 2 is a front side view of the design for a road construction machine of FIG. 1.

FIG. 3 is a right side view of the design for a road construction machine of FIG. 1.

FIG. 4 is a rear side view of the design for a road construction machine of FIG. 1.

FIG. 5 is a top side view of the design for a road construction machine of FIG. 1.

FIG. 6 is the bottom side view of the design for a road construction machine of FIG. 1.

FIG. 7 is a perspective view of the front side, left side and top side of the design for a road construction machine of FIG. 1.

FIG. 8 shows a further perspective view of the rear side, right side and top side of the design for a road construction machine for FIG. 1.

FIG. 9 is a left side view of a second embodiment of the design for a road construction machine of the present invention.

FIG. 10 is a front side view of the design for a road construction machine of FIG. 9.

FIG. 11 is a right side view of the design for a road construction machine of FIG. 9.

FIG. 12 is a rear side view of the design for a road construction machine of FIG. 9.

FIG. 13 is a top side view of the design for a road construction machine of FIG. 9.

FIG. 14 is a bottom side view of the design for a road construction machine of FIG. 9.

FIG. 15 shows a perspective view onto the front side, left side and top side of the design for a road construction machine of FIG. 9; and,

FIG. 16 shows a further perspective view onto the rear side, right side and top side of the design for a road construction machine of FIG. 9.

1 Claim, 16 Drawing Sheets
